Inventor:

UNITED STATES PATENT OFFICE.

THOMAS M. DUDGEON, OF CRAFTON, PENNSYLVANIA, ASSIGNOR TO PITTSBURGH STOVE AND RANGE COMPANY, OF PITTSBURG, PENNSYLVANIA, A CORPORATION OF PENNSYLVANIA.

DESIGN FOR A BASKET-GRADE.

SPECIFICATION forming part of Design No. 36,054, dated September 9, 1902.

Application filed July 29, 1902. Serial No. 117,574. Term of patent 7 years.

To all whom it may concern:

Be it known that I, THOMAS M. DUDGEON, a citizen of the United States, residing at Crafton, in the county of Allegheny and State of Pennsylvania, have invented a new, original, and ornamental Design for Basket-Grates, of which the following is a full, clear, and exact description, reference being had to the accompanying drawing, forming part hereof, in which the invention is shown in perspective.

The leading features of the design consist of a solid back piece having an overhanging arched ledge along its central upper edge, the outer edge of the ledge being formed of oppositely-extending scrolls. From the arched central ledge the top edge of the back piece is concavely curvilinear in outline. At the center of the back piece, in relief, is a medallion bearing the representation of a woman's head, and extending up from the lower central portion of the back piece at the sides of the head are scroll-like streamers, in relief. The front piece of the grate consists of an open framework having a central convex basket-weave

portion inclosed in a peripheral molding. 25 Above the top edge of the molding is an open-work portion formed of a series of wreaths in a horizontal row surmounted by a molding having volute ends and a plume-like central portion. The central basket-weave portion 30 is connected to the sides of the grate by inwardly-turned scrolls. The back and front parts of the grate are connected by side pieces having scrolled top edges terminating on the inner surfaces of the sides in spiral volutes. 35 Below the front piece is a frame extending for the width thereof.

I claim—

The ornamental design for a basket-grate as herein shown and described. 40

In testimony whereof I have hereunto set my hand in the presence of two subscribing witnesses.

THOMAS M. DUDGEON.
